Primary Examiner—Marcus A. Jackson

Attorney, Agent, or Firm—Saidman DesignLaw Group[57] **CLAIM**

The ornamental design for an auxiliary lamp for an automobile, as shown and described.

DESCRIPTION

FIG. 1 is a top perspective view of an auxiliary lamp for an automobile showing my new design;

FIG. 2 is a front plan view thereof;

FIG. 3 is a rear plan view thereof;

FIG. 4 is a right side view thereof;

FIG. 5 is a left side view thereof;

FIG. 6 is a top plan view thereof;

FIG. 7 is a bottom plan view thereof; and,

FIG. 8 is a bottom perspective view thereof.

The small, white electrical connector and attached wiring shown incidentally in FIGS. 3, 4, 5, 6 and 7 are environmental only and form no part of the claimed design.

The letters “PIAA” appearing on the front of the translucent glass portions in FIGS. 1, 2 and 8 are environmental only and form no part of the claimed design.
